UNITED STATES PATENT OFFICE.

FRANK P. DUNN, OF ANDERSON, INDIANA.

VENDING-MACHINE.

1,107,660.

Specification of Letters Patent. Patented Aug. 18, 1914.

Application filed September 11, 1913. Serial No. 789,281.

To all whom it may concern:

Be it known that I, FRANK P. DUNN, a citizen of the United States, residing at Anderson, in the county of Madison and State of Indiana, have invented a new and useful 5 Vending-Machine, of which the following is a specification.

The object of my invention is to produce a neat, efficient but cheap and simple device 10 for the vending of articles, more particularly small boxes of matches.

The accompanying drawings illustrate my invention.

Figure 1 is a front elevation of an apparatus embodying my invention; Fig. 2 a rear elevation; Fig. 3 a fragmentary section on line 3—3 of Fig. 6; Fig. 4 is a fragmentary section on line 4—4 of Fig. 5, with the coin admission guard plate removed; 20 Fig. 5 is a fragmentary central vertical section through the coin-handling mechanism; and Fig. 6 a fragmentary section on line 6—6 of Fig. 2.

In the drawings, 10 indicates a hollow base having coin pockets 11, 11 separated by a pedestal 12 having a transverse coin groove 13 in its upper end.

Erected from the base 10 is a reservoir 14 provided with two storage compartments 30 15, 15 which are defined by the outer walls 16, 16 and the intermediate wall 17 all of which, at their lower ends, terminate in a plane some distance above the base so as to form a transverse passageway or pocket in 35 which is mounted a slide 18. The slide 18 comprises a main bottom plate provided at its middle with a raised platform 19, the width of which is greater than half the width of one of the storage compartments. 40 At each end of the main bottom plate of the slide is erected a guard flange 20 and along one side is a wall 21 which connects the flanges 20 with the platform 19 and thus forms two delivery recesses 22, 22 each having an open end which, in the present embodiment of my invention, opens rearwardly. The storage compartments 15, 15 are closed by means of a removable back plate 23 which is conveniently perforated in 45 order that the articles within the storage compartments may be readily viewed and this back plate near its lower end is provided with side notches 24, 24 which are in alinement with the delivery pockets 22, 22

50 but are so proportioned that only one of the delivery pockets may fully register with

an adjacent notch 24 at one time. The lower end of plate 23 is projected downwardly behind lugs 26, 26 carried by the base 10 and the upper end of plate 23 is 60 perforated to receive a perforated ear 27 carried by the casing 14 and arranged to receive a suitable lock 28.

In order to carry the delivery slide fully to either of its delivery positions, I provide 65 said slide with two downwardly projecting pins 30, 30. In the base I arrange two upwardly projecting standards 31, 31 to the upper end of each of which is pivoted a lever 32. The two levers are arranged to 70 operate upon the opposite sides of the two pins 30, 30 and are provided with a surface 34 which, when the lever is swung to the relative position shown at the left of Fig. 6 engages the adjacent pin 30 at such angle 75 as to have no shifting effect upon the slide but, when the slide has been moved materially in the direction toward its next delivery position, the adjacent pin 30 will be carried beyond the surface 34 and into contact with an adjacent portion of the lever the angle of which is such as to have a strong driving effect upon the slide to drive it to its full delivery position.

By removing the cover plate 23, the storage compartments 15 may be filled with the articles to be delivered, such, for instance, as the small match boxes 35, said articles having a vertical height a trifle less than the distance between the upper face of the bottom plate of the slide 18 and the lower ends of the partitions 16 and 17 and a little greater than the height of platform 19 above the upper face of the bottom plate of the slide. The slide 18 is of such length that, in 95 its two extreme positions its end walls 20 will alternately register, or substantially register, with the side walls 16 of the storage compartments and only one of the delivery recesses will ever be fully exposed 100 opposite the notches 24.

If it is desired to prevent actuation of the slide 18 except upon deposit of the proper coin, the slide 18 is provided at its front with a horizontal flange 39 through 105 which extend two coin slots 40 which may be brought into alternate registry above the coin slot 13 of the pedestal 12. The flange 39 is provided at its outer edge with an up-standing flange 41 which is provided at its 110 opposite ends with oppositely arranged ratchet teeth 42 adapted to be engaged by

pawls 43 which are urged into active position by light springs 44. A limited amount of play of the slide may be had before the main pawl 42 engages the first shoulder of the adjacent ratchet 42 and each pawl is adapted to rest upon the upper face of the first tooth of the adjacent ratchet and be thereby supported at such distance from the bottom of the coin groove 13 that, when 10 a coin is introduced through the receiving slot 45 and drops by gravity into the alined slot 40 and rests in the bottom of groove 13, the end of the adjacent pawl 43 will lie close to the periphery of the coin and somewhat above the center of the coin so that, when a push is exerted in the proper direction upon the slide 18 the coin will be driven under the adjacent pawl 43 so as to lift it free from the adjacent ratchet 42 and permit 15 the slide to be projected laterally as indicated by dotted lines in Fig. 3. This ejection of the slide will cause the platform 19 to strip the lowermost box 35 from the forward stack of boxes, the platform thus passing out from under the rear stack of boxes so as to permit that stack to drop down into the rear recess 22, and passing beneath the second box from the bottom in the forward stack so as to retain that portion of 25 the stack within the storage compartment. As the slide is driven to its new position the deposited coin is carried beyond the pedes-

tal 12 and drops into one of the pockets 11 and when the slide has been fully projected, the article which has been stripped from the bottom of the forward stack is brought into registry with the adjacent notch 24 so that it can be readily withdrawn from the slot. 35

I have found it convenient to provide the base 10 with a cigar clipper 50 of well known form. 40

I claim as my invention:

In a dispensing apparatus a shiftable delivery member having a coin slot, a double ended ratchet adjacent said coin slot, a coin support arranged to support a coin with its center beyond the ratchet, and a pair of oppositely arranged pawls arranged to contact with the opposite portions of the ratchet in the path of movement of the coin where- 45 by a coin lying within the coin slot and resting upon the coin support will, when driven laterally by the shiftable member, have its periphery driven beneath the active pawl to shift the same out of the path of 50 movement of the adjacent ratchet. 55

In witness whereof, I have hereunto set my hand at Indianapolis, Indiana, this 9th day of September, A. D. one thousand nine hundred and thirteen.

FRANK P. DUNN.
